ABSTRACT OF THE DISCLOSURE

This invention relates to novel unsaturated 2-oxa steroid derivatives of the formula

wherein R is alkyl having from 1 to 6 carbon atoms, X is selected from the group consisting of hydrogen, alkyl having from 1 to 5 carbon atoms, alkenyl having from 3 to 5 carbon atoms, cycloalkyl having from 5 to 7 carbon atoms, aralkyl having from 7 to 11 carbon atoms, cycloalkylalkyl having from 4 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms, as well as the process of preparing the same. These compounds have an anabolic action coupled with an androgenic action.

BENEFIT OF COPENDING APPLICATIONS

This application is a continuation-in-part of our co-pending applications Ser. No. 603,094, filed Dec. 20, 1966, and Ser. No. 603,457, filed Dec. 21, 1966, both now abandoned.

OBJECTS OF THE INVENTION

An object of the invention is the obtention of an unsaturated 2-oxa steroid derivative of the formula

wherein R is alkyl having from 1 to 6 carbon atoms, X is selected from the group consisting of hydrogen, alkyl having from 1 to 5 carbon atoms, alkenyl having from 3 to 5 carbon atoms, cycloalkyl having from 4 to 7 carbon atoms, aralkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms.

Another object of the invention is the development of a process for the production of the above unsaturated 2-oxa

2

steroid derivatives which comprises the steps of condensing a 10 - hydroxymethyl - des - A - $\Delta^{9,11}$ -gonadiene-5-one of the formula

wherein R is alkyl having from 1 to 6 carbon atoms, X is selected from the group consisting of hydrogen, alkyl having from 1 to 5 carbon atoms, alkenyl having from 3 to 5 carbon atoms, cycloalkyl having from 4 to 7 carbon atoms, aralkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms, with a lower alkyl haloacetate in the presence of zinc, reacting the resulting condensation products, a mixture of (1) a 5 - alkoxy carbonylmethyl - 10 - hydroxymethyl - des - A - $\Delta^{9,11}$ -gonadiene of the formula

wherein R and X have the above-assigned meanings and alkyl represents a lower alkyl, and (2) a 2-oxa- $\Delta^{9,11}$ -gonadiene-5-ol-3-one of the formula

wherein R and X have the above-assigned meanings, with a strong acid after optional saponification of the 5-alkoxycarbonylmethyl derivative, and recovering said unsaturated 2-oxa steroid derivatives.

A further object of the invention is the development of a process for the production of the above unsaturated 2-oxa steroid derivatives which comprises the steps of condensing a 10-hydroxymethyl-des-A- $\Delta^{9,11}$ -gonadiene-5-one of the formula

wherein R is alkyl having from 1 to 6 carbon atoms and acyl represents the acyl of an organic carboxylic acid having from 1 to 18 carbon atoms, with a lower alkyl haloacetate in the presence of zinc, saponifying the resulting condensation products, a mixture of (1) a 5-alkoxycar-

bonylmethyl - 10 - hydroxymethyl - des - A- $\Delta^{9,11}$ -gonadiene of the formula

wherein R and acyl have the above-assigned meanings and alkyl represents a lower alkyl, and (2) 2-oxa- $\Delta^{9,11}$ -gonadiene-5-ol-3-one of the formula

wherein R and acyl have the above-assigned meanings, by the action of a saponifying agent, reacting the resulting products, a mixture containing as a major part of a 2-oxa- $\Delta^{9,11}$ -gonadiene of the formula

wherein R has the above-assigned meaning, with a strong acid, and recovering said unsaturated 2-oxa steroid derivative.

A yet further object of the invention is the obtention of intermediate compounds selected from the group consisting of (1) a 5-alkoxycarbonylmethyl-10-hydroxymethyl-des-A- $\Delta^{9,11}$ -gonadiene of the formula

wherein R is alkyl having from 1 to 6 carbon atoms, X is selected from the group consisting of hydrogen, alkyl having from 1 to 5 carbon atoms, alkenyl having from 3 to 5 carbon atoms, cycloalkyl having from 5 to 7 carbon atoms, aralkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms, and alkyl represents lower alkyl, and (2) a 2-oxa- $\Delta^{9,11}$ -gonadiene-5-ol-3-one of the formula

wherein R is alkyl having from 1 to 6 carbon atoms, X is selected from the group consisting of hydrogen, alkyl hav-

ing from 1 to 5 carbon atoms, alkenyl having from 3 to 5 carbon atoms, cycloalkyl having from 5 to 7 carbon atoms, aralkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms.

A still further object of the invention is the obtention of a therapeutic composition containing a minor amount of the above 2-oxa steroid derivative and a major amount of a pharmaceutical carrier.

Another object of the invention is the development of a process for the treatment of warm-blooded animals with an anabolic and androgenic agent which comprises administering to said warm-blooded animals a daily dose of from 0.003 mg./kg. to 0.3 mg./kg. of the above 2-oxa steroid derivative.

These and other objects of the invention will become more apparent as the description thereof proceeds.

DESCRIPTION OF THE INVENTION

In particular, the invention relates to the 2-oxa- $\Delta^{9,11}$ -gonatriene-3-ones of the general Formula I

wherein, here and later on, R is an alkyl radical having from 1 to 6 carbon atoms, and X is selected from the group consisting of hydrogen, alkyl having from 1 to 5 carbon atoms, alkenyl having from 3 to 5 carbon atoms, cycloalkyl having from 5 to 7 carbon atoms, aralkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms and the acyl of an organic carboxylic acid having from 1 to 18 carbon atoms.

In the general Formula I, the alkyl R is by preference one of the following: methyl, ethyl, propyl, butyl; the alkyl radical X which can include a hetero atom between 2 carbon atoms is advantageously the methoxymethyl or the methylthiomethyl and the acyl X is advantageously selected from the group consisting of the acyl of aliphatic, saturated or unsaturated, carboxylic acids or of aromatic or heterocyclic carboxylic acids, of hexahydrobenzoic acid, of cyclopentyl-, cyclohexyl-, or phenylacetic or propionic acids, of phenoxyalkanoic acids, of furan-2-carboxylic acids, 5-tert-butylfuran-2-carboxylic acids, of β -ketocarboxylic acids, among others.

Preferably, in the general Formula I, R can be methyl, ethyl and propyl; and X can be hydrogen, alkyl having from 1 to 5 carbon atoms such as methyl, ethyl, propyl, etc., alkenyl having from 3 to 5 carbon atoms, such as Δ^1 -propenyl, methylallyl, dimethylallyl, etc., cycloalkyl having from 5 to 7 carbon atoms, such as cyclopentyl or cyclohexyl, cycloalkylalkyl having from 6 to 11 carbon atoms, such as hexahydrobenzyl or substituted hexahydrobenzyl, alkoxyalkyl having from 2 to 5 carbon atoms, such as methoxymethyl, ethoxyethyl, etc., alkylthioalkyl having from 2 to 5 carbon atoms, such as methylthiomethyl and the like, and the acyl of an organic carboxylic acid having from 1 to 18 carbon atoms selected from the group consisting of alkanoic acids, such as acetic acid, propionic acid, lauric acid, etc., alkenoic acids such as oleic acid, etc., benzoic acid, hexahydrobenzoic acid, cycloalkylalkanoic acids, such as cyclopentyl-, cyclohexyl-, acetic or propionic acids, etc., phenylalkanoic acids such as phenylacetic acid, phenylpropionic acid, etc., heterocyclic carboxylic acids such as furan-2-carboxylic

5

acid, 5-ter-butylfuran-2-carboxylic acids, etc., and β -keto-alkanoic acids such as acetylacetic acid, etc.

The compounds of the general Formula I possess useful pharmacological properties. In particular, these compounds distinguish themselves from 2-oxa-17 α -methyl-17 β -hydroxy-19-nor-androstane-3-one (Presse Medicale [1963] 71, pp. 1319-20) by a far superior anabolic action.

The compounds of the general Formula I are particularly endowed with a high anabolic activity, and, in addition, for some of them, an androgenic activity.

Among the compounds of the general Formula I, the following are especially interesting:

13 β -methyl-17 β -acetoxy-2-oxa- $\Delta^{4,9,11}$ -gonatriene-3-one
 13 β -methyl-17 β -(methoxy)-methoxy-2-oxa- $\Delta^{4,9,11}$ -gonatriene-3-one
 13 β -methyl-17 β -benzyloxy-2-oxa- $\Delta^{4,9,11}$ -gonatriene-3-one
 13 β -ethyl-17 β -acetoxy-2-oxa- $\Delta^{4,9,11}$ -gonatriene-3-one
 13 β -ethyl-17 β -benzyloxy-2-oxa- $\Delta^{4,9,11}$ -gonatriene-3-one
 13 β -methyl-17 β -hexahydrobenzyloxy-2-oxa- $\Delta^{4,9,11}$ -gonatriene-3-one
 13 β -methyl-17 β -benzyloxy-2-oxa- $\Delta^{4,9,11}$ -gonatriene-3-one
 13 β -methyl-17 β -(methylthio)-methoxy-2-oxa- $\Delta^{4,9,11}$ -gonatriene-3-one
 13 β -methyl-17 β -(3'-methyl-2'-butenyl)-2-oxa- $\Delta^{4,9,11}$ -gonatriene-3-one
 13 β -methyl-17 β -(2'-methyl) allyloxy 2-oxa- $\Delta^{4,9,11}$ -gonatriene-3-one.

Thus, 13 β -methyl-17 β -acetoxy-2-oxa- $\Delta^{4,9,11}$ -gonatriene-3-one possesses important anabolic and androgenic actions which are quite superior to those of 19-nor-testosterone acetate. Moreover, it is active when given orally and its action is clearly superior to that of the 17 α -methyl-19-nor-testosterone.

13 β -methyl-17 β -(methoxy)-methoxy-2-oxa- $\Delta^{4,9,11}$ -gonatriene-3-one possesses an important anabolic action and a moderated androgenic action. The anabolic activity of this product is very superior to that of 17 α -methyltestosterone. A daily dose of 20 γ of 13 β -methyl-17 β -(methoxy)-methoxy-2-oxa- $\Delta^{4,9,11}$ -gonatriene-3-one has already a strong anabolic action on the animal, and its androgenic effect is only slightly perceptible.

13 β -methyl-17 β -benzyloxy-2-oxa- $\Delta^{4,9,11}$ -gonatriene-3-one possesses important anabolic and androgenic actions which are quite superior to those of 19-nor-testosterone acetate and 17 α -methyl-19-nor-testosterone both when administered orally and subcutaneously.

13 β -ethyl-17 β -acetoxy-2-oxa- $\Delta^{4,9,11}$ -gonatriene-3-one possesses a clearly superior anabolic action than 19-nor-testosterone acetate and has a much greater androgenic action.

The process for the preparation of the compounds of the general Formula I is characterized in that a 10-hydroxymethyl-des-A- $\Delta^{9,11}$ -gonadiene-5-one of the general Formula II

6

hydroxy - methyl - des - A- $\Delta^{9,11}$ -gonadiene of the general Formula III

5

10

and 2-oxa- $\Delta^{9,11}$ -gonadiene-5-ol-3-one of the general Formula IIIa

15

20

25 is treated with a strong acid agent after optional saponification of the 5-alkoxycarbonylmethyl derivative, and the desired 2-oxa- $\Delta^{4,9,11}$ -gonatriene-3-one of the general Formula I is isolated, which, in the desired case, is subjected, when the said compound comprises a 17-hydroxyl function, to the action of an esterification agent to form the corresponding 17-ester, or to the action of an etherification agent to form the corresponding 17-ether.

30 It is preferred to utilize the benzoate ester in the synthesis of the invention. However, the 17-ethers and the 17-alcohol can also be utilized. Among the 17-ethers are the 17 β -methoxy, the 17 β -ethoxy, and 17 β -allyloxy, the 17 β -methoxymethoxy, etc.

The execution of the process of the invention can also be characterized by the following points:

40 (1) The lower alkyl haloacetate is selected from the group consisting of methyl or ethyl bromoacetate, methyl or ethyl chloroacetate and methyl or ethyl iodoacetate.

45 (2) The strong acid agent is selected from the group consisting of a strong mineral acid, such as hydrochloric acid, sulfuric acid or perchloric acid, and a strong organic acid, such as p-toluenesulfonic acid or methane sulfonic acid.

(3) The esterification agent is selected from the group consisting of an organic carboxylic acid containing from 1 to 18 carbon atoms, and a functional derivative thereof such as an acid anhydride or an acid chloride.

(4) The esterification agent is a saturated or unsaturated alkyl halide, containing from 1 to 5 carbon atoms, possibly including an oxygen atom between two carbon atoms, such as methoxy-chloromethane or dialkyl sulfoxide.

50 A variation of the process of the invention is characterized in that a 10-hydroxymethyl-17 β -acyloxy-des-A- $\Delta^{9,11}$ -gonadiene-5-one of the general formula

65

70

the R being defined as indicated in the preceding and acyl represents an acyl of an organic carboxylic acid having from 1 to 18 carbon atoms, is condensed with a lower alkyl haloacetate in the presence of zinc. The resultant condensation product, formed by a mixture of a 5-hy-

is condensed with a lower alkyl haloacetate in the presence of zinc. The resultant condensation product, a mixture of a 5-hydroxy-5-alkoxycarbonylmethyl-10-

75

7

droxy - 5 - alkoxycarbonylmethyl-10-hydroxymethyl-17 β -acyloxy-des-A- $\Delta^9,11$ -gonadiene of the general formula

and of a 17 β -acyloxy-2-oxa- $\Delta^9,11$ -gonadiene-5-ol-3-one of the general formula

is treated with a saponification agent to obtain the corresponding 17-hydroxyl compound. The saponified mixture is subjected to the action of a strong acid agent, and the desired 2-oxa- $\Delta^4,9,11$ -gonatriene-17 β -ol-3-one is isolated, which, in this case, if desired, is subjected to the action of an esterification agent to form the corresponding 17-ester or to the action of an etherification agent to form the corresponding 17-ether.

The execution of the variation of the process of the invention can also be characterized by the following points:

- (1) The saponification agent is an alkali metal hydroxide in the presence of a lower alkanol such as methanolic sodium or potassium hydroxide.
- (2) The lower alkyl haloacetate, the strong acid agent, the esterification agent and the etherification agent are as given in the preceding.

The starting products of the present process of the general Formula II are obtained by the processes of formylating a des-A- Δ^9 -gonene of the formula

dehydrogenating the resulting 10-hydroxymethylene derivative and reducing the resulting 10-formyl derivative to obtain the starting products of the general Formula II, or of condensing an enamine of the formula

with a mixed formic-acetic acid anhydride, hydrolyzing the resulting 10-hydroxymethylene iminium derivative, dehydrogenating the resulting 10-hydroxymethylene derivative and reducing the resulting 10-formyl derivative to obtain the starting products of the general Formula II. These processes are further described in copending commonly assigned U.S. patent application Ser. No. 603,094, filed Dec. 20, 1966 now abandoned.

8

The starting products of the Formula V

5

wherein R has the above-assigned meaning and X' is selected from the group consisting of alkyl having from 1 to 5 carbon atoms, alkenyl having from 3 to 5 carbon atoms, cycloalkyl having from 4 to 7 carbon atoms, alkoxalkyl having from 2 to 5 carbon atoms, aralkyl having from 7 to 11 carbon atoms, cycloalkyl-alkyl having from 4 to 11 carbon atoms, and alkylthioalkyl having from 2 to 5 carbon atoms, may also be prepared by the processes consisting of (A) formylating a des-A- Δ^9 -gonene of the formula

wherein Acyl represents the acyl radical of an organic carboxylic acid having from 1 to 18 carbon atoms and R has the above-assigned meaning, to obtain a 10-hydroxymethylene derivative of the Formula IV

wherein R and acyl have the above-assigned meanings, or (B) condensing an enamine of the formula

wherein R₂ and R₃ are selected from the group consisting of alkyl having from 1 to 8 carbon atoms, and, when taken together, alkyne having from 4 to 5 carbon atoms and alkyne-oxy-alkyne having 4 carbon atoms, and R and Acyl have the above-assigned meanings, with a mixed formic-acetic acid anhydride, hydrolyzing the resulting 10-hydroxymethylene iminium derivative of the formula

wherein R, R₂, R₃ and Acyl have the above-assigned meanings to obtain a 10-hydroxymethylene derivative of Formula IV, reducing said 10-hydroxymethylene deriva-

tive, reacting the 10-formyl-des-A- $\Delta^{9,11}$ -gonadiene-5-one thus formed, of the formula

wherein R and Acyl have the above-assigned meanings, with a ketalizing agent, saponifying the resultant diketal of the formula

wherein K is a ketal group, R and Acyl have the above-assigned meanings, by the action of an alkaline agent, etherifying the resultant 17 β -ol derivative of the formula

wherein K and R have the above-assigned meanings, by the action of a halogenide of the formula X'-Hal, wherein Hal is a halogen atom other than fluorine, and X' is as herein before defined, subjecting the resultant 17-ether of the formula

wherein R, K and X' have the above-assigned meanings, to an acid hydrolysis, reducing the resultant 10-formyl-des-A-gonadiene of the formula

wherein R and X' have the above-assigned meanings, to the action of a mixed hydride, and recovering the 10-hydroxymethyl derivative of Formula V.

The execution of the previous process of preparing the starting products of Formula V may also be effected in the following manner:

(a) the ketalizing agent is selected from the group consisting of the lower cyclic ketals, for example 2-methyl-2-ethyl-dioxolane, and the lower alkanediols, for

example ethyleneglycol. The reaction is conducted in the presence of an acid catalyst.

(b) The alkaline agent used in the saponification step is an alkali metal hydroxide, such as sodium or potassium hydroxide, in the presence of a lower alkanol such as methanol or ethanol.

(c) The etherification step is carried out in the presence of a basic agent, such as sodium hydride, in a polar solvent such as tetrahydrofuran, dimethylformamide or dimethylsulfoxide.

(d) The mixed hydride is selected from the group consisting of an alkali metal borohydride, such as sodium borohydride, and an alkali metal hydridotrialkoxoaluminate, such as lithium hydridotriisobutoxidoaluminate. The reaction is preferably performed in aqueous dioxane in the first case, and in tetrahydrofuran in the second case.

The following examples will serve for a better comprehension of the invention without, however, limiting the scope of the invention in any manner.

EXAMPLE I

Preparation of 13 β -methyl-17 β -benzoyloxy-2-oxa- $\Delta^{4,9,11}$ -gonatriene-3-one

(A) Condensation: 3 gm. of 10-hydroxymethyl-13 β -methyl-17 β -benzoyloxy-des-A- $\Delta^{9,11}$ -gonadiene-5-one (as described in U.S. patent application Ser. No. 603,094) were dissolved in 45 cc. of anhydrous benzene, then 3 gm. of zinc and an iodine crystal were added. Next, under good agitation and within the space of 10 minutes, 3 cc. of ethyl bromoacetate were introduced into the mixture heated approximately to reflux. The reaction was strongly exothermic. The reflux was maintained for about 10 minutes after the end of the introduction of the reactant.

The reaction mixture was then cooled. The organic solution was washed first with an aqueous iced solution of hydrochloric acid, then with water, dried, distilled to dryness, and the residue obtained was subjected to chromatography through silica gel, with elution with a 50% mixture of benzene and ethyl acetate.

In this manner, 2.78 gm. of a mixture of 5-hydroxy-5-carboethoxymethyl-10-hydroxymethyl-13 β -methyl-17 β -benzoyloxy-des-A- $\Delta^{9,11}$ -gonadiene and 5-hydroxy-13 β -methyl-17 β -benzoyloxy-2-oxa- $\Delta^{9,11}$ -gonadiene-3-one were isolated, which mixture was used as such in the following step of the synthesis.

5 - hydroxy - 13 β - methyl-17 β -benzoyloxy-2-oxa- $\Delta^{9,11}$ -gonadiene-3-one can be isolated from the mixture indicated above by crystallization from methanol. Its melting point was 226° C. with a specific rotation $[\alpha]_D^{20} = +39^\circ$ (c.=0.5% in chloroform).

Analysis.—Calculated for $C_{24}H_{26}O_5$ (percent): Molecular weight = 394.45. C, 73.07; H, 6.64. Found (percent): C, 73.0; H, 6.7.

This compound is not described in the literature.

(B) Acid treatment: 2.78 gm. of the raw mixture, obtained under (A), were dissolved in 20 cc. of benzene under an atmosphere of nitrogen; then 0.25 gm. of p-toluenesulfonic acid was added and the reaction mixture was heated at reflux for about 10 minutes.

The benzenic solution was washed first with an aqueous solution of sodium bicarbonate, then with water, dried, distilled to dryness, and in this way, 13 β -methyl-17 β -benzoyloxy-2-oxa- $\Delta^{4,9,11}$ -gonatriene-3-one was obtained.

The product had a melting point of 186° to 187° C. and a specific rotation $[\alpha]_D^{20} = +130.5^\circ$ (c.=0.55% in chloroform).

This compound is not described in the literature.

EXAMPLE II

Preparation of 13 β -methyl-17 β -hydroxy-2-oxa- $\Delta^{4,9,11}$ -gonatriene-3-one

(A) Condensation: This step was effected exactly in the manner as described in Example I.

(B) Saponification: 2.78 gm. of the raw mixture, obtained under (A), were dissolved in 27 cc. of methanol

11

under an atmosphere of nitrogen; then 2.8 cc. of potassium hydroxide solution were added and the reaction mixture was heated at reflux for one hour.

Thereafter, the reaction mixture was cooled and 3.5 cc. of hydrochloric acid were added thereto. Next, the reaction mixture was poured into water and extracted with methylene chloride. The extracts were washed first with a saturated aqueous solution of sodium bicarbonate, then with salt water, lastly with water, dried and distilled to dryness.

In this manner, 1.92 gm. of a product was isolated containing as a major part 13β -methyl-5,17 β -dihydroxy-2-oxa- $\Delta^{9,11}$ -gonadiene-3-one, which product was used as such for the next step of the synthesis.

13β -methyl-5,17 β -dihydroxy-2-oxa- $\Delta^{9,11}$ -gonadiene-3-one could be isolated from the raw product indicated above by subjecting it to chromatography through silica gel and by crystallization of the eluate from methanol. The melting point was 204° C.

Ultraviolet spectra (ethanol):

λ_{max} . 242-243 m μ , ϵ =18,200

Infrared spectra (chloroform):

γ lactone at 1,740 cm. $^{-1}$

This compound is not described in the literature.

(C) Acid treatment: 1.92 gm. of the raw product, obtained under (B), were dissolved in 10 cc. of methanol under an atmosphere of nitrogen. Then 2 cc. of chloroform and 1 cc. of concentrated hydrochloric acid were added, and the reaction mixture was allowed to stand for $\frac{1}{2}$ hour at room temperature.

Thereafter, the reaction mixture was poured into water and extracted with methylene chloride. The organic extract was washed first with a saturated aqueous solution of sodium bicarbonate, then with salt water and lastly with pure water, dried and distilled to dryness.

The residue obtained was crystallized from ethyl acetate, thus obtaining 1.28 gm. of 13β -methyl-17 β -hydroxy-2-oxa- $\Delta^{4,9,11}$ -gonatriene-3-one, which after recrystallization from methylethylketone, had a melting point of 222° C. and a specific rotation of $[\alpha]_D^{20}=+26.9^\circ$ (c.=0.69% in chloroform). The yield of crystallization amounted to 70% of the theory.

The product was insoluble in ether, slightly soluble in alcohol, and soluble in chloroform.

Ultraviolet spectra (ethanol):

λ_{max} .—230 m μ , ϵ =5,720; 328 m μ , ϵ =27,230

(N/10 sodium hydroxide in ethanol):

λ_{max} . 232 m μ and 304 m μ

Infrared spectra:

γ lactone—

at 1,706 cm. $^{-1}$ with a shoulder

at 1,722 and 1,688 cm. $^{-1}$

Analysis.—Calculated for $C_{17}H_{20}O_3$ (percent): Molecular weight=272.33. C, 74.97; H, 7.4. Found (percent): C, 74.9; H, 7.6.

This compound is not described in the literature.

The 13β -methyl-17 β -hydroxy-2-oxa- $\Delta^{4,9,11}$ -gonatriene-3-one as described in the preceding, was identical to the compound obtained by saponification of 13β -methyl-17 β -benzoyloxy-2-oxa- $\Delta^{4,9,11}$ -gonatriene-3-one described in Example I. This saponification can be effected in the following manner.

1 gm. of 13β -methyl-17 β -benzoyloxy-2-oxa- $\Delta^{4,9,11}$ -gonatriene-3-one was admixed with 10 cc. of methanol and 1 cc. of 10 N potassium hydroxide solution, and the mixture was heated at reflux for about 20 minutes. Thereafter, the reaction mixture was acidified by the addition of 1.5 cc. of concentrated hydrochloric acid, poured into water and extracted with methylene chloride.

The methylene chloride extract was washed first with a saturated aqueous solution of sodium bicarbonate, then with water, dried and distilled to dryness, and 13β -methyl-17 β -hydroxy-2-oxa- $\Delta^{4,9,11}$ -gonatriene-3-one was isolated.

12

EXAMPLE III

Preparation of 13β -methyl-17 β -benzoyloxy-2-oxa- $\Delta^{4,9,11}$ -gonatriene-3-one

5 50.4 gm. of zinc and 1.18 gm. of iodine were introduced into a solution of 50.4 gm. of 10-hydroxymethyl- 13β -methyl-17 β -benzoyloxy-des- $\Delta^{9,11}$ -gonadiene-5-one (obtained as described in Belgian Patent 691,404) in 765 cc. of benzene. Then a third of a solution of 50.4 cc. of ethyl bromoacetate in 114 cc. of benzene was added thereto, and the mixture was refluxed for 25 minutes. Next, the rest of the ethyl bromoacetate solution was added and the reflux was maintained for an additional 20 minutes. Then, the temperature was brought to 25° C. and the mixture was filtered. The filtrate was washed with benzene. The combined benzenic phases were washed first with an aqueous hydrochloric acid solution, then with water, dried over sodium sulfate and evaporated to dryness. The residue was subjected to chromatography through silica gel and eluted with a benzene-ethyl acetate mixture (5—5). In this manner, 24 gm. of amorphous product were recovered which was used as such for the remainder of the synthesis.

20 6 gm. of the amorphous product, previously obtained, were dissolved in 36 cc. of acetic acid. 3.6 cc. of 2 N hydrochloric acid were added and the mixture was agitated for 2 hours and 30 minutes at room temperature. Next, 12 cc. of water were added and crystallization commenced. 100 cc. of a water-ice mixture were added and the mixture was again agitated for 30 minutes and finally vacuum filtered. The precipitate was washed with water and dried. Thus, 4.46 gm. of raw 13β -methyl-17 β -benzoyloxy-2-oxa- $\Delta^{4,9,11}$ -gonatriene-3-one were recovered.

25 The raw product was purified by chromatography through silica gel, elution with a benzene-ethyl acetate mixture (7—3) and by recrystallization with heating and cooling from ethyl acetate. 2.1 gm. of 13β -methyl-17 β -benzoyloxy-2-oxa- $\Delta^{4,9,11}$ -gonatriene-3-one were obtained with a melting point of 188° to 189° C.

30 35 Analysis.—Calculated for $C_{24}H_{24}O_4$ (percent): Molecular weight=376.43. C, 76.57; H, 6.42. Found (percent): C, 76.4; H, 6.6.

Infrared spectra (chloroform):

absence of OH

presence of benzoate

presence of complexed carbonyl at—

1,721 cm. $^{-1}$, 1,709 cm. $^{-1}$, 1,692 cm. $^{-1}$

Ultraviolet spectra (ethanol):

max. at 230 m μ $E_{1\text{cm.}}^{1\%}$ =524

max. at 324 m μ $E_{1\text{cm.}}^{1\%}$ =772 or ϵ =29,100

35 The 13β -methyl-17 β -benzoyloxy-2-oxa- $\Delta^{4,9,11}$ -gonatriene-3-one occurred in the form of pale yellow needles, soluble in chloroform, alcohol and methylene chloride and insoluble in water.

40 The product had a melting point, determined on the Kofler block of 188° to 189° C. and a specific rotation $[\alpha]_D^{20}=+129^\circ \pm 2^\circ$ (c.=1% in chloroform).

This compound is not described in the literature.

45 The 13β -methyl-17 β -benzoyloxy-2-oxa- $\Delta^{4,9,11}$ -gonatriene-3-one may also be prepared in the following manner:

50 500 mg. of 13β -methyl-2-oxa- $\Delta^{4,9,11}$ -gonatriene-17 β -ol-3-one were dissolved in 2 cc. of pyridine. The solution was cooled to +5° C. and 0.75 cc. of benzoyl chloride were added, without exceeding +10° C. The mixture was agitated over 2 hours at +5° C. and then it was allowed to stand over a period of 17 hours in the refrigerator. Thereafter, 0.6 cc. of formic acid were added. The reaction mixture was agitated for one hour at +5° C. to +10° C., and then it was poured into a mixture of a saturated aqueous solution of sodium bicarbonate, water and ice. Next, the reaction mixture was extracted with methylene chloride. The methylene chloride phases were 55 washed first with N hydrochloric acid, then with a satu-

rated aqueous solution of sodium bicarbonate and lastly with water, then dried over sodium sulfate and distilled to dryness, in vacuo. 0.98 gm. of raw 13β -methyl- 17β -benzoyloxy-2-oxa- $\Delta^{4,9,11}$ -gonatriene-3-one were recovered, which was purified by chromatography through silica gel, elution with a benzene-ethyl acetate mixture (7-3) and recrystallization from methanol. In this manner, 0.298 gm. of 13β -methyl- 17β -benzoyloxy-2-oxa- $\Delta^{4,9,11}$ -gonatriene-3-one were obtained, identical to that previously obtained.

In the same manner as described in Examples I and II, the work was conducted by starting with 10-hydroxymethylated tricyclic derivatives, but having in the 13-position an alkyl other than methyl such as ethyl, propyl, isopropyl, butyl, isobutyl, leading in the corresponding 2-oxa steroid derivative.

EXAMPLE IV

Preparation of 13β -methyl- 17β -acetoxy-2-oxa- $\Delta^{4,9,11}$ -gonatriene-3-one

Under an atmosphere of nitrogen and at room temperature, 0.8 gm. of 13β -methyl- 17β -hydroxy-2-oxa- $\Delta^{4,9,11}$ -gonatriene-3-one were introduced into 3.2 cc. of pyridine. Then 1.6 cc. of acetic acid anhydride were added and the reaction mixture was agitated for 4½ hours.

The excess of the reactant was destroyed by addition of water, then the reaction mixture was again agitated for a few minutes, and then acidified with concentrated hydrochloric acid to bring about crystallization. Then, the mixture was diluted with water and agitated for one hour. The crystals were vacuum filtered and washed until the wash waters were neutral.

After drying, the raw product was subjected to chromatography through silica and eluted with a benzene-ethyl acetate mixture (1-1).

In this manner, with a yield of 87% of the theory, 13β -methyl- 17β -acetoxy-2-oxa- $\Delta^{4,9,11}$ -gonatriene-3-one was obtained which, after recrystallization from isopropanol, had a melting point of 110° C. and a specific rotation $[\alpha]_D^{20} = +61^\circ$ (c.=0.56% in chloroform).

Ultraviolet spectra (ethanol):

λ_{max}
at 229-230 m μ , $\epsilon = 6,160$
and
at 324 m μ , $\epsilon = 27,400$

Infrared spectra (chloroform):

γ lactone at 1,708 and 1,689 cm. $^{-1}$
 $\text{C}=\text{C}$ bond at 1,593 and 1,562 cm. $^{-1}$

The product was insoluble in water, and soluble in ethanol and chloroform.

Analysis.—Calculated for $\text{C}_{19}\text{H}_{22}\text{O}_4$ (percent): Molecular weight=314.37. C, 72.58; H, 7.05. Found (percent): C, 72.7; H, 7.1.

This compound is not described in the literature.

EXAMPLE V

Preparation of 13β -methyl- 17β -(methoxy)-methoxy-2-oxa- $\Delta^{4,9,11}$ -gonatriene-3-one

2.72 gm. of 13β -methyl- 17β -hydroxy-2-oxa- $\Delta^{4,9,11}$ -gonatriene-3-one were dissolved in 30 cc. of dimethylformamide, and 2 cc. of chloromethyl-methyl ether were added thereto. Then the mixture was allowed to stand for 2 hours at room temperature. Thereafter, again 2 cc. of chloromethyl-methyl ether were added and the mixture was allowed to react for 16 hours at room temperature. Next, the reaction mixture was poured into a saturated aqueous solution of sodium bicarbonate and extracted with methylene chloride. The combined organic phases were washed first with a sodium bicarbonate solution, then with water until the wash waters were neutral, dried over sodium sulfate and concentrated to dryness under vacuum. By this method, 3.12 gm. of an oily product were recovered, which was subjected to chromatography through

silica gel and eluted first with a chloroform-ethyl acetate mixture (1 to 1), then with a benzene-ethyl acetate mixture (7 to 3). In this way, 2.16 gm. of 13β -methyl- 17β -(methoxy)-methoxy-2-oxa- $\Delta^{4,9,11}$ -gonatriene-3-one were obtained, representing a yield of 70% of the theory. After recrystallization from isopropanol the product had a melting point of 110° to 111° C. and a specific rotation $[\alpha]_D^{20} = +34^\circ$ (c.=0.5% in chloroform).

Analysis.—Calculated for $\text{C}_{19}\text{H}_{24}\text{O}_4$ (percent): Molecular weight=316.38. C, 72.12; H, 7.65. Found (percent): C, 71.9; H, 7.7.

Ultraviolet spectra (ethanol):

λ_{max}
at 229-230 m μ , $\epsilon = 6,000$
and
at 326 m μ , $\epsilon = 27,950$
(ethanol-N/10 NaOH)
 λ_{max}
at 229 m μ , $\epsilon = 3,800$
and
at 304 m μ , $\epsilon = 23,550$

The product occurred in the form of clear yellow crystals, soluble in the usual organic solvents, and insoluble in water, in dilute aqueous acids and in dilute aqueous alkalies.

This compound is not described in the literature.

EXAMPLE VI

Preparation of 13β -ethyl- 17β -benzoyloxy-2-oxa- $\Delta^{4,9,11}$ -gonatriene-3-one

STEP A—PREPARATION OF 10-HYDROXYMETHYLENE- 13β -ETHYL- 17β -BENZOYLOXY-DES-A- $\Delta^{9(11)}$ -GONENE-5-ONE

At room temperature, under agitation and an atmosphere of nitrogen 27.23 gm. of 5-pyrrolidino- 13β -ethyl- 17β -benzoyloxy-DES-A- $\Delta^{5(10),9(11)}$ -gonadiene (obtained according to the process described in U.S. Pat. No. 3,168,530) were dissolved in 272 cc. of dioxane and 136 cc. of tetrahydrofuran. Then, 20 cc. of triethylamine and, while maintaining the temperature between 0° C. and +5° C., 50 cc. of formic-acetic acid anhydride (obtained by the action of sodium formate on the acetyl chloride) were added thereto. Next, the mixture was agitated for 3 hours

and 30 minutes. Then, 110 cc. of water were added and the reaction mixture was allowed to stand overnight at room temperature. Thereafter, the reaction mixture was poured into a water-ice mixture. The precipitate was extracted with ether. The ethereal phases were separated and

washed with water, then extracted with N/2 sodium hydroxide-ice mixture. The alkaline phases were acidified with hydrochloric acid to a pH of 1, and extracted with ether. The ethereal phases were washed with water, dried and distilled to dryness. The residue obtained was purified

by dissolution in hot ethanol, which was then allowed to return to room temperature. Next, the mixture was iced for 30 minutes and vacuum filtered. The precipitate was washed first with iced ethanol, then with petroleum ether and finally dried. 14.72 gm. of 10-hydroxymethylene- 13β -ethyl- 17β -benzoyloxy-DES-A- $\Delta^{9(11)}$ -gonene-5-one were obtained in the form of clear, yellow crystals, soluble in acetone, chloroform and methanol, and insoluble in water. The product had a melting point of 118° C. and a specific rotation $[\alpha]_D^{20} = +58^\circ \pm 2^\circ$ (c.=0.5% in chloroform).

Analysis.—Calculated for $\text{C}_{23}\text{H}_{26}\text{O}_4$ (percent): Molecular weight=366.44. C, 75.38; H, 7.15. Found (percent): C, 75.1; H, 6.9.

This compound is not described in the literature.

STEP B—PREPARATION OF 10-FORMYL- 13β -ETHYL- 17β -BENZOYLOXY-DES-A- $\Delta^{9,11}$ -GONADIENE-5-ONE

A room temperature, under agitation and an atmosphere of nitrogen, 14.72 gm. of 10-hydroxymethylene- 13β -ethyl- 17β -benzoyloxy-DES-A- $\Delta^{9(11)}$ -gonene-5-one were dissolved in a mixture of 75 cc. of dioxane and 75 cc. of ether. A solution of 10.5 gm. of dicyanodichloro-

benzoquinone in 75 cc. of dioxane was added while maintaining the interior temperature between 8° C. and 10° C. Then, the mixture was agitated over a period of 45 minutes at room temperature. Next, the reaction mixture was poured into an iced solution of sodium bicarbonate and sodium bisulfite and extracted with ether. The ethereal phases were washed first with a mixture of 0.1 N sodium hydroxide and ice, then with water and finally distilled to dryness. 7.47 gm. of raw product were thus recovered, which was purified by chromatography through a column of alumina and elution with methylene chloride. In this manner, after evaporation of the solvent, 5.33 gm. of 10-formyl-13β-ethyl-17β-benzoyloxy - des - A - $\Delta^{9,11}$ -gonadiene-5-one were obtained, which product was used as such in the next step.

This compound is not described in the literature.

STEP C—PREPARATION OF 10-HYDROXYMETHYL-13β-ETHYL-17β-BENZOYLOXY - DES - A - $\Delta^{9,11}$ -GONADIENE-5-ONE

At room temperature, under agitation and an atmosphere of nitrogen, 5.42 gm. of 10-formyl-13β-ethyl-17β-benzoyloxy-des-A- $\Delta^{9,11}$ -gonadiene - 5 - one were dissolved in 54 cc. of dioxane. The temperature was brought to +5° C., and 180 mg. of sodium borohydride were added to the solution. The reaction mixture was kept under agitation for one hour, then poured into a water-ice mixture. The mixture was then extracted with methylene chloride. Next, the methylene chloride phases were washed with water, dried and distilled to dryness. The resultant residue was subjected to chromatography through alumina and eluted with methylene chloride. After the evaporation of the solvent, 3.15 gm. of 10-hydroxymethyl-13β-ethyl-17β-benzoyloxy-des-A- $\Delta^{9,11}$ -gonadiene - 5 - one were obtained. The product was utilized as such for the following step.

For analysis, the product was recrystallized from ether and petroleum ether. This compound occurred in the form of yellowish crystals, soluble in acetone, chloroform and alcohol, and insoluble in water. It had a melting point of 90° C. and a specific rotation $[\alpha]_D^{20} = -74 \pm 2^\circ$ (c. = 0.2% in chloroform).

Analysis.—Calc'd for $C_{23}H_{26}O_4$ (percent): Molecular weight = 366.44. C, 75.38; H, 7.15. Found (percent): C, 75.2; H, 7.3.

This compound is not described in the literature.

STEP D—PREPARATION OF 13β-ETHYL-17β-BENZOYL-OXY-2-OXA- $\Delta^{4,9,11}$ -GONATRIENE-3-ONE

(1) Preparation of the zinc reactant: Under an atmosphere of nitrogen, 13 gm. of zinc and 25 mg. of mercuric chloride in 50 cc. of methylal were heated to reflux. Then, 11 cc. of ethyl bromoacetate were added and the reflux was maintained for 15 minutes. Thereafter, 50 cc. of methylal were added and the reaction mixture was again refluxed for an additional 15 minutes. Then the excess of zinc was decanted, thus obtaining a clear solution of zinc derivative of ethyl bromoacetate.

(2) Condensation: At room temperature, under agitation and an atmosphere of nitrogen, 940 mg. of 10-hydroxymethyl-13β-ethyl - 17β - benzoyloxy - des - A - $\Delta^{9,11}$ -gonadiene-5-one were dissolved in 20 cc. of tetrahydrofuran. Next, 20 cc. of the solution of the zinc reactant, obtained as described in the preceding, were added and the mixture was refluxed for 3 hours. Thereafter, the mixture was cooled, poured into ice and brought to a pH of 1 by an addition of 2 N hydrochloric acid. The acidified mixture was extracted with methylene chloride containing 10% of methanol, decanted and distilled to dryness. In this manner, 5β-hydroxy-5β-carboethoxymethyl-10-hydroxymethyl-13β-ethyl - 17β - benzoyloxy - des - A - $\Delta^{9,11}$ -gonadiene was obtained. The product was utilized as such for the next step.

This compound is not described in the literature.

(3) Cyclization into 13β-ethyl-17β-benzoyloxy-2-oxa- $\Delta^{4,9,11}$ -gonatriene-3-one: At room temperature, under agitation and an atmosphere of nitrogen, 5β-hydroxy-5β-

carboethoxymethyl-10-hydroxymethyl - 13β - ethyl - 17β-benzoyloxy-des-A- $\Delta^{9,11}$ -gonadiene, obtained above, was dissolved in 10 cc. of acetic acid. Next, 1 cc. of 2 N hydrochloric acid was added and the reaction mixture was agitated for 2 hours. Thereafter, the reaction mixture was poured into water and extracted with methylene chloride. The organic phases were washed first with water, then with a solution of sodium bicarbonate and again with water. The organic solution was treated with carbon black, filtered and distilled to dryness. The residue was dissolved in hot ether, cooled, isopropyl ether was added and the mixture was iced. The precipitate was vacuum filtered, washed with isopropyl ether and dried, thus obtaining 570 mg. of 13β-ethyl-17β-benzoyloxy-2-oxa- $\Delta^{4,9,11}$ -gonatriene-3-one in the form of pale yellow crystals, soluble in acetone, chloroform and alcohol, and insoluble in water. The compound had a melting point of 176° C. and a specific rotation $[\alpha]_D^{20} = +145^\circ$ (c. = 0.43% in chloroform).

Analysis.—Calc'd for $C_{25}H_{26}O_4$ (percent): Molecular weight = 390.46. C, 76.90; H, 6.71. Found (percent): C, 76.8; H, 6.7.

This compound is not described in the literature.

EXAMPLE VII

Preparation of 13β-ethyl-2-oxa- $\Delta^{4,9,11}$ -gonatriene-17β-ol-3-one

1.74 gm. of 13β-ethyl-17β-benzoyloxy-2-oxa- $\Delta^{4,9,11}$ -gonatriene-3-one were suspended in 45 cc. of methanol. 1.2 cc. of N-methanolic potassium hydroxide were added thereto and the mixture was refluxed for 2 hours and 30 minutes. Thereafter, the mixture was cooled, brought to a pH of 7 by an addition of acetic acid, then poured into water and extracted with methylene chloride. The organic phases were washed with water, dried and distilled to dryness. The residue thus obtained was dissolved in 125 cc. of hot ether. The solution was concentrated to about 10 cc. Then 5 cc. of isopropyl ether were added and again concentrated to 10 cc. Next, the mixture was allowed to stand for 30 minutes at room temperature, then vacuum filtered. The precipitate was washed with isopropyl ether and dried. In this manner, 0.99 gm. of 13β-ethyl-2-oxa- $\Delta^{4,9,11}$ -gonatriene-17β-ol-3-one were obtained in the form of pale yellow crystals, soluble in acetone, chloroform and alcohols, and insoluble in water, with a melting point of 143° C. and a specific rotation $[\alpha]_D^{20} = +43 \pm 2^\circ$ (c. = 0.5% in chloroform).

Analysis.—Calculated for $C_{18}H_{22}O_3$ (percent): Molecular weight = 286.37. C, 75.49; H, 7.74. Found (percent): C, 75; H, 7.8.

This compound is not described in the literature.

EXAMPLE VIII

Preparation of 13β-ethyl-17β-acetoxy-2-oxa- $\Delta^{4,9,11}$ -gonatriene-3-one

At room temperature, under agitation and an atmosphere of nitrogen, 0.99 gm. of 13β-ethyl-2-oxa- $\Delta^{4,9,11}$ -gonatriene-17β-ol-3-one was dissolved in 9 cc. of pyridine. 4.5 cc. of acetic acid anhydride were added and the reaction mixture was maintained at 45° C. for 2 hours and 30 minutes. The excess of acetic acid anhydride was destroyed by an addition of water. The reaction mixture was poured over a mixture of ice and 2 N hydrochloric acid and adjusted to a pH of 1 by 2 N hydrochloric acid. The acidified solution was extracted with methylene chloride. The organic phases were washed with water, dried and distilled to dryness. The resultant residue was dissolved in ether at room temperature. Isopropyl ether was added to the reaction mixture, which was allowed to stand for 15 minutes at room temperature; then it was vacuum filtered. The precipitate was washed with isopropyl ether and dried. Thus, 803 mg. of 13β-ethyl-17β-acetoxy-2-oxa- $\Delta^{4,9,11}$ -gonatriene-3-one were obtained. The product had a melting point of 85° C. (Kofler Block) and a spe-

specific rotation $[\alpha]_{D}^{20} = +75^{\circ} \pm 3^{\circ}$ (c.=0.5% in chloroform).

The product occurs in the form of colorless crystals, soluble in chloroform, acetone, alcohol and ether, and insoluble in water.

Analysis.—Calculated for $C_{20}H_{24}O_4$ (percent): Molecular weight=328.41. C, 73.14; H, 7.37. Found (percent): C, 72.9; H, 7.3.

Ultraviolet spectra:

max. at 229-230 m μ , $E_{1\text{cm}}^{1\%} = 184$

max. at 325 m μ , $E_{1\text{cm}}^{1\%} = 870$

This compound is not described in the literature.

EXAMPLE IX

Preparation of 13β -methyl- 17β -benzyloxy-2-oxa- $\Delta^{4,9,11}$ -gonatriene-3-one

STEP A: PREPARATION OF 5 - ETHYLEDIOXY-10-(ETHYLEDIOXY) METHYL - 13β - METHYL - 17β - BENZOYLOXY-DES-A- $\Delta^{9,11}$ -GONADIENE

5 gm. of 10-formyl- 13β -methyl- 17β -benzyloxy-des-A- $\Delta^{9,11}$ -gonadiene-5-one (as described in U.S. patent application No. 603,094) and 0.15 gm. of paratoluene sulfonic acid were introduced into 150 cc. of chloroform and 15 cc. of ethylene glycol under an atmosphere of nitrogen. The mixture was heated to reflux under agitation for 30 hours; the distillate was dried over a dehydrating agent before being recycled. Then 0.05 gm. of paratoluene sulfonic acid was added and the mixture was again heated to reflux under the previously described conditions for 15 hours. The reaction mixture was cooled, made alkaline by addition of triethylamine and diluted with water. The aqueous phase was extracted with methylene chloride, and the extracts were combined with the organic phase. The organic solution thus obtained was washed with water, dried, and evaporated to dryness under reduced pressure. The residue was chromatographed over silica gel and eluted with an ethyl acetate-benzene mixture (1-9). 2.4 gm. of raw mono-ketal (M.P. 192° C.) were first eluted, then 1.7 gm. of raw diketal (M.P. 175° C.) was collected.

After recrystallization of the raw diketal from ethanol, 1.27 gm. of pure 5-ethylenedioxy-10-(ethylenedioxy) methyl- 13β -methyl - 17β - benzyloxy-des-A- $\Delta^{9,11}$ -gonadiene, having a melting point of 176° C., was obtained.

Analysis.—Calculated for $C_{26}H_{30}O_6$ (percent): Molecular weight=334.40. C, 68.24; H, 7.84. Found (percent): 71.2; H, 7.2.

Ultraviolet spectrum (in ethanol):

max. at 239-240 m μ , $\epsilon=32,850$.

STEP B: PREPARATION OF 5-ETHYLEDIOXY - 10-(ETHYLEDIOXY) METHYL - DES - A - $\Delta^{9,11}$ -GONADIENE- 17β -OL

A mixture of 4.77 gm. of 5-ethylene dioxy-10-(ethylenedioxy) methyl- 13β -methyl- 17β -benzyloxy-des-A- $\Delta^{9,11}$ -gonadiene and 48 cc. of a N potassium hydroxide solution in 95% ethanol was heated to reflux for 30 minutes and then 250 cc. of water were added. The reaction mixture was extracted with methylene chloride. The organic phases were washed with water, dried over sodium sulfate, filtered and evaporated to dryness under vacuum to yield 3.8 gm. of raw 17β -hydroxy derivative. 200 mg. of raw product were pasted in isopropyl ether at reflux temperature. After cooling, the precipitate was filtered, washed with isopropyl ether and dried, whereby 175 mg. (92% yield) of product were obtained. This product was purified by recrystallization from ethyl acetate, thus affording 105 mg. of 5-ethylenedioxy-10-(ethylenedioxy) methyl - 13β - methyl-des-A- $\Delta^{9,11}$ -gonadiene- 17β -ol. The product occurred in the form of colorless crystals, soluble in ethanol and methylene chloride, insoluble in water, and melting at 183° C.

Analysis.—Calculated for $C_{19}H_{26}O_5$ (percent): Molecular weight=334.40. C, 68.24; H, 7.84. Found (percent): C, 68.4; H, 7.5.

Ultraviolet spectrum (in ethanol):
max. at 247 m μ , $\epsilon=23,200$

STEP C: PREPARATION OF 5 - ETHYLEDIOXY-10-(ETHYLEDIOXY) METHYL - 13β - METHYL - 17β - BENZOYLOXY-DES-A- $\Delta^{9,11}$ -GONADIENE

5 gm. of 5-ethylenedioxy-10-(ethylenedioxy)methyl- 13β -methyl- 17β -hydroxy-des-A- $\Delta^{9,11}$ -gonadiene were dissolved in 180 cc. of terahydrofuran. Then 3.2 gm. of a suspension of 50% sodium hydride in paraffin oil were added to the solution, and the whole was heated to reflux for 30 minutes. Then 12.5 cc. of benzyl bromide were added, and the heating at reflux was continued for a period of 90 minutes. The reaction mixture was cooled to room temperature and poured into a mixture of water, ice and aqueous sodium hydroxide solution. The aqueous phase was extracted with methylene chloride, the extracts were combined, washed with water, dried and concentrated to dryness. The residue was triturated with petroleum ether (B.P. 65-75° C.) to afford 7.65 gm. of 5-ethylenedioxy-10-(ethylenedioxy) methyl- 13β -methyl - 17β - benzyloxy-des-A- $\Delta^{9,11}$ -gonadiene melting at 160° C.

The analytical sample, M.P. 163° C., was obtained by recrystallization from methanol containing 2 parts per thousand of triethylamine.

Analysis.—Calculated for $C_{26}H_{32}O_5$ (percent): Molecular weight=424.52. C, 73.57; H, 7.59. Found (percent): C, 73.5; H, 7.8.

Ultraviolet spectrum (in ethanol):

max. at 246 m μ , $\epsilon=23,600$

STEP D: PREPARATION OF 10 - FORMYL- 13β -METHYL- 17β -BENZOYLOXY-DES-A- $\Delta^{9,11}$ -GONADIENE-5-ONE

Under an atmosphere of nitrogen, 7.98 gm. of 5-ethylenedioxy-10-(ethylenedioxy) methyl - 13β - methyl- 17β -benzyloxy-des-A- $\Delta^{9,11}$ -gonadiene were dissolved in 60 cc. of acetic acid, then 20 cc. of water were added and the mixture was stirred at room temperature for 1 hour. Then a water-ice mixture was added, and the precipitate thus formed was vacuum-filtered, washed with water and dried to yield 6.05 gm. of raw 10-formyl- 13β -methyl- 17β -benzyloxy-des-A- $\Delta^{9,11}$ -gonadiene-5-one, having a melting point of 120° C., which product was used as such in the next step.

STEP E: 10-HYDROXYMETHYL- 13β -METHYL- 17β -BENZOYLOXY-DES-A- $\Delta^{9,11}$ -GONADIENE-5-ONE

Under an atmosphere of nitrogen, 6.84 gm. of raw 10-formyl- 13β -methyl- 17β -benzyloxy-des-A- $\Delta^{9,11}$ -gonadiene-5-one were dissolved in 70 cc. of dioxane. The mixture was cooled to +10° C., and a cold solution of 0.200 gm. of sodium borohydride in 7 cc. of water was added dropwise. The reaction mixture was stirred for 20 minutes, and 0.020 gm. of sodium borohydride was then added. After an additional stirring at +10° C. for 10 minutes, the mixture was poured into water. The aqueous layer was extracted with methylene chloride the combined extracts were washed, first with water, then with a N/10 sodium hydroxide aqueous solution and finally with water. The extracts were dried and concentrated to dryness. The residue was purified by chromatography through silica gel to afford 4.14 gm. of 10-hydroxymethyl- 13β -methyl- 17β -benzyloxy-des-A- $\Delta^{9,11}$ -gonadiene 5-one, having a melting point of 115° C., which product was used as such in the next step.

STEP F: PREPARATION OF 13β -METHYL- 17β -BENZOYLOXY-2-OXA- $\Delta^{9,11}$ -GONATRIENE-3-ONE

(1°) Reformatsky reaction—Preparation of 5-carbethoxy-methyl-10-hydroxymethyl- 13β -methyl - 17β - benzyloxy-des-A- $\Delta^{9,11}$ -gonadiene-5-ol: 3.5 gm. of 10-hydroxymethyl- 13β -methyl- 17β -benzyloxy - des-A- $\Delta^{9,11}$ -gonadiene 5-one were dissolved in 35 cc. of benzene and 36.5 cc. of a 0.86 M solution of zinc derivative of ethyl bromoacetate in dimethoxy-methane were added to the solution thus obtained. The reaction mixture was heated to reflux for 30 minutes, then cooled to room temperature and poured into a water-ice-hydrochloric acid mixture. The

aqueous layer was extracted with methylene chloride, the combined extracts were washed with water, dried and evaporated to dryness giving substantially the 5-carbethoxymethyl-10-hydroxymethyl-13 β -methyl-17 β -benzyl-oxy-des-A- $\Delta^{9,11}$ -gonadiene-5-ol (5 gm. yield).

(2°) Acid treatment—(a) Treatment with a methanol-hydrochloric acid mixture: 5 gm. of the residue obtained under (1°) were introduced, under nitrogen, in 50 cc. of methanol, then 7.5 cc. of water and 5 cc. of 35% hydrochloric acid aqueous solution. The reaction mixture was stirred at room temperature for 15 hours. The precipitate was vacuum-filtered, washed and dried to yield 2.5 gm. of a crystalline product, M.P. 115° C., consisting of 12-methoxy-13 β -methyl-17 β -benzyl-oxo- $\Delta^{5(10),9(11)}$ -gonadiene-3-one. The mother liquors and wash waters were combined and evaporated to dryness thereby affording another 1.5 gm. of the same material.

(b) Treatment with a methanol-acetic acid-hydrochloric acid mixture: 2.45 gm. of said product were introduced, while agitating, into 17 cc. of acetic acid. Then 25 cc. of methanol and 2.5 cc. of 35% hydrochloric acid aqueous solution were added to the solution thus obtained. The reaction mixture was stirred at room temperature for 1 hour, then an ice-water mixture was added. The precipitate thus formed was vacuum-filtered, washed and dried. There were obtained 2.15 gm. of 13 β -methyl-17 β -benzyl-oxo-2-oxo- $\Delta^{4,9,11}$ -gonatriene-3-one, having a melting point of 134° C.

A sample of this compound was crystallized from ethyl acetate. It had a melting point of 136° C. and a specific rotation $[\alpha]_D^{20} = +32.5^\circ$ (c.=0.5% in chloroform).

Analysis.—Calculated for $C_{24}H_{26}O_3$ (percent): Molecular weight=362.45. C, 79.52; H, 7.23. Found (percent): C, 79.3; H, 7.2.

Ultraviolet spectrum (in ethanol):

max. at 229 m μ , $\epsilon=6,500$
inflection at about 256 to 257 m μ , $\epsilon=3,180$
max. at 325 m μ , $\epsilon=28,400$

EXAMPLE X

Preparation of 13 β -methyl-17 β -hexahydrobenzyl-oxo-2-oxa- $\Delta^{4,9,11}$ -gonatriene-3-one

STEP A: 5-ETHYLEDIOXY-10-(ETHYLEDIOXY)METHYL-13 β -METHYL-17 β -HEXAHYDROBENZYL-OXY-DES-A- $\Delta^{9,11}$ -GONADIENE

By following the procedure of step C of Example IX, 5-ethylenedioxy-10-(ethylenedioxy) methyl-13 β -methyl-des-A- $\Delta^{9,11}$ -gonadiene-17 β -ol was reacted in a dimethyl sulfoxide-tetrahydrofuran mixture with hexahydrobenzyl bromide to give 5-ethylenedioxy-10-(ethylenedioxy) methyl-13 β -methyl-17 β -hexahydrobenzyl-oxo-2-oxa- $\Delta^{4,9,11}$ -gonadiene, having a melting point of 180° C. and a specific rotation $[\alpha]_D^{20} = -122^\circ$ (c.=0.5% in chloroform).

Ultraviolet spectrum (in ethanol):

max. at 247 m μ , $\epsilon=23,700$

This compound is not described in the literature.

STEP B: 10-FORMYL-13 β -METHYL-17 β -HEXAHYDROBENZYL-oxo-DES-A- $\Delta^{9,11}$ -GONADIENE-5-ONE

Following the procedure of step D of Example IX, 5-ethylenedioxy-10-(ethylenedioxy) methyl-13 β -methyl-17 β -hexahydrobenzyl-oxo-2-oxa- $\Delta^{4,9,11}$ -gonadiene was converted by acetic acid hydrolysis, into 10-formyl-13 β -methyl-17 β -hexahydrobenzyl-oxo-DES-A- $\Delta^{9,11}$ -gonadiene-5-one, having a melting point of 107° C. and a specific rotation $[\alpha]_D^{20} = -115^\circ$ (c.=0.6% in chloroform). This material was used as such in the next step.

STEP C: 10-HYDROXYMETHYL-13 β -METHYL-17 β -HEXAHYDROBENZYL-oxo-DES-A- $\Delta^{9,11}$ -GONADIENE-5-ONE

By following the procedure of step E of Example IX, the material obtained under (b) was converted by treatment with sodium borohydride into raw 10-hydroxy-methyl-13 β -methyl-17 β -hexahydrobenzyl-oxo-DES-A-

$\Delta^{9,11}$ -gonadiene-5-one, which was used as such for the next step.

STEP D: 13 β -METHYL-17 β -HEXAHYDROBENZYL-oxo-DES-A- $\Delta^{4,9,11}$ -GONATRIENE-3-ONE

(1°) Reformatsky reaction—Preparation of 5-carbethoxymethyl-10-hydroxymethyl-13 β -methyl-17 β -hexahydrobenzyl-oxo-DES-A- $\Delta^{4,9,11}$ -gonadiene-5-one: 1.07 gm. of the material obtained under (C) was dissolved under nitrogen in 20 cc. of tetrahydrofuran; then 14.7 cc. of a 0.85 M solution of zinc derivative of ethyl bromoacetate in dimethoxymethane were added to the solution. The reaction mixture was stirred at room temperature for 30 minutes and then it was poured into water. Methylene chloride was added thereto, and the mixture was acidified with a dilute hydrochloric acid aqueous solution. The organic layer was separated, washed with water, dried and concentrated to dryness to yield 1.5 gm. of material containing substantially 5-carbethoxymethyl-10-hydroxymethyl-13 β -methyl-17 β -hexahydrobenzyl-oxo-DES-A- $\Delta^{4,9,11}$ -gonadiene-5-one.

(2°) Acid treatment: The raw material obtained under (1°) was dissolved in 15 cc. of acetic acid under nitrogen, and 1 cc. of a 2 N hydrochloric acid aqueous solution was added. The reaction mixture was stirred at room temperature for 45 minutes, and then poured into water. The aqueous phase was extracted with methylene chloride and the extracts were washed with water, dried and evaporated to dryness. The residue subjected to chromatography through silica gel and to elution with an ethyl acetate-benzene mixture (1-9), gave 0.796 gm. of 13 β -methyl-17 β -hexahydrobenzyl-oxo-DES-A- $\Delta^{4,9,11}$ -gonatriene-3-one having a melting point of 92° C.

A sample of this product was again subjected to chromatography and recrystallized from diethyl ether. It melted at 97° to 98° C. and had a specific rotation $[\alpha]_D^{20} = +22^\circ$ (c.=0.3% in chloroform).

Analysis.—Calculated for $C_{24}H_{32}O_3$ (percent): Molecular weight=368.50. C, 78.22; H, 8.75. Found (percent): C, 78.1; H, 8.8.

Ultraviolet spectrum (in ethanol):

max. at 229 to 230 m μ , $\epsilon=6,220$
max. at 326 m μ , $\epsilon=28,400$

EXAMPLE XI

Preparation of 13 β -methyl-17 β -(2'-methyl)allyloxy-2-oxa- $\Delta^{4,9,11}$ -gonatriene-3-one

STEP A: 5-ETHYLEDIOXY-10-(ETHYLEDIOXY)METHYL-13 β -METHYL-17 β -BENZOYL-oxo-DES-A- $\Delta^{4,9,11}$ -GONADIENE

This compound was obtained as described in Example IX step A.

STEP B: PREPARATION OF 5-ETHYLEDIOXY-10-(ETHYLEDIOXY)METHYL-13 β -METHYL-17 β -BENZOYL-oxo-DES-A- $\Delta^{4,9,11}$ -GONADIENE-17 β -OL

This compound was obtained as described in Example IX step B.

STEP C: 5-ETHYLEDIOXY-10-(ETHYLEDIOXY)METHYL-13 β -(2'-METHYL)ALLYLOXY-DES-A- $\Delta^{4,9,11}$ -GONADIENE

2.4 gm. of a suspension of 50% sodium hydride in mineral oil and 24 cc. of tetrahydrofuran were stirred at room temperature under nitrogen for a period of 5 minutes. A solution of 4.09 gm. of 5-ethylenedioxy-10-(ethylenedioxy) methyl-13 β -methyl-DES-A- $\Delta^{4,9,11}$ -gonadiene-17 β -ol in 50 cc. of tetrahydrofuran was added thereto and the whole was heated to reflux for 30 minutes.

A solution of 9 gm. of β -methylallyl chloride in 36 cc. of tetrahydrofuran was then added and the whole was heated to reflux for 18 hours. After cooling, 300 cc. of water were added, and the reaction mixture was extracted with methylene chloride. The extracts were washed with water, dried over sodium sulfate, filtered, and evaporated to dryness under vacuum, thus yielding 5.55 gm. of raw 17 β -methylallyl derivative which was recrystallized from isopropyl ether (yield 2.44 gm.).

21

Another crystallization from isopropyl ether afforded an analytical sample which occurred in the form of colorless needles, soluble in ethanol and methylene chloride and insoluble in water. It melted at 137° C. and had a specific rotation $[\alpha]_D^{20} = -160^\circ \pm 4^\circ$ (c. = 0.2% in chloroform).

Analysis.—Calculated for $C_{23}H_{32}O_5$ (percent): Molecular weight = 388.49. C, 71.10; H, 8.30. Found (percent): C, 71.1; H, 8.3.

Ultraviolet spectrum (in ethanol):

max. at 246 to 247 $m\mu$, $\epsilon = 23,100$

This compound is not described in the literature.

STEP D: PREPARATION OF 10-FORMYL-13 β -METHYL-17 β -(2'-METHYL) ALLYLOXY-DES-A- $\Delta^{9,11}$ -GONADIENE-5-ONE

A solution of 2.2 gm. of 5-ethylenedioxy 10-(ethylene-dioxy) methyl-13 β -methyl-17 β -(2'-methyl) allyloxy-des-A- $\Delta^{9,11}$ -gonadiene in 16.5 cc. of acetic acid and 5.5 cc. of water was stirred under nitrogen for 1 hour at room temperature and then poured into 400 cc. of saturated aqueous solution of sodium bicarbonate. The mixture was extracted with methylene chloride, and the extracts were washed with water until the wash waters were neutral, dried over sodium sulfate, filtered and evaporated to dryness. There was obtained 1.73 gm. of 10-formyl-13 β -methyl-17 β -(2-methyl) allyloxy-des- $\Delta^{9,11}$ -gonadiene-5-one which occurred in the form of yellow prisms, soluble in acetic acid and methylene chloride, insoluble in water. The material melted at about 58° C.

Ultraviolet spectrum (in ethanol):

max. at 233 $m\mu$, $\epsilon = 6,450$

max. at 309 $m\mu$; $\epsilon = 19,500$

This compound is not described in the literature.

STEP E: PREPARATION OF 10-HYDROXYMETHYL-13 β -METHYL-17 β -METHYL-(2'-METHYL) ALLYLOXY-DES-A- $\Delta^{9,11}$ -GONADIENE-5-ONE

2.92 gm. of 10-formyl-13 β -methyl-17 β -(2'-methyl) allyloxy-des-A- $\Delta^{9,11}$ -gonadiene-5-one were introduced into 30 cc. of dioxane and 3 cc. of water. After cooling to +8° C., 100 mg. of sodium borohydride were added, the mixture was stirred at +10° C. for a period of 30 minutes, poured into a saturated aqueous solution of sodium chloride and extracted with methylene chloride. The organic phases were washed with water, dried over sodium sulfate, filtered and evaporated to dryness, thus yielding 2.8 gm. of raw 10-hydroxymethyl derivative which was purified by chromatography through silica gel followed by elution with an ethyl acetate-benzene mixture (5-5). In this way, 1.28 gm. of 10-hydroxymethyl-13 β -methyl-17 β -(2'-methyl) allyloxy-des-A- $\Delta^{9,11}$ -gonadiene-5-one was obtained in the form of colorless crystals, soluble in methylene chloride, benzene and ethyl acetate, insoluble in water, and melting at 102° C.

Ultraviolet spectrum (in ethanol):

max. at 309 $m\mu$, $\epsilon = 19,500$

This compound is not described in the literature.

STEP F: PREPARATION OF 13 β -METHYL-17 β -(2'-METHYL) ALLYLOXY-2-OXA- $\Delta^{4,9,11}$ -GONATRIENE-3-ONE

(1°) Reformatsky reaction: Under an atmosphere of nitrogen, 1.25 gm. of 10-hydroxymethyl-13 β -methyl-17 β -(2'-methyl) allyloxy-des-A- $\Delta^{9,11}$ -gonadiene-5-one, 1.25 gm. of zinc and 0.02 gm. of iodine were introduced into 20 cc. of benzene. Then 1.5 cc. of a solution obtained by dissolving 1.78 cc. of ethyl bromoacetate in 4.5 cc. of benzene was added, and the whole was heated at 105° C. for a period of 10 minutes. The remainder of the solution of ethyl bromoacetate was then added and the reflux was maintained for 20 minutes. The reaction mixture was then cooled and filtered. The filter was washed with 5 cc. of benzene and the combined filtrates were poured into 70 cc. of an N hydrochloric acid solution.

22

After decantation and extraction with methylene chloride, the organic phases were combined, washed with water till neutrality, dried over sodium sulfate and evaporated to dryness to afford 1.9 gm. of adduct.

(2°) Saponification of the adduct: 1.7 gm. of the material obtained under (1°) was dissolved at 20° C. in 17 cc. of methanol. Then 2.5 cc. of 8 N potassium hydroxide solution were added and the mixture was heated to reflux, under nitrogen, for 30 minutes. 3.4 cc. of hydrochloric acid were added after cooling and the reaction mixture was then poured into water. The mixture was extracted with methylene chloride, the organic phases were washed with a saturated aqueous solution of sodium bicarbonate, then with water till neutrality, dried over sodium sulfate and evaporated to dryness. There was obtained 1.33 gm. of saponified product.

(3°) Cyclodehydration: The material obtained under (2°) was dissolved in 7 cc. of methanol and 0.7 cc. of hydrochloric acid and the solution was stirred for 1 hour. The reaction mixture was then poured into water and extracted with methylene chloride. The extracts were washed with a saturated aqueous solution of sodium bicarbonate, then with water until the wash waters became neutral, and evaporated to dryness. There was obtained 1.22 gm. of 2-oxa triene derivative which was subjected to chromatography through silica gel, eluted with an ethyl acetate-benzene mixture (9-1) and recrystallized from cyclohexane and then from ethyl acetate to give 13 β -methyl-17 β -(2'-methyl) allyloxy-2-oxa- $\Delta^{4,9,11}$ -gonatriene-3-one which melted at 108° C.

Analysis.—Calculated for $C_{21}H_{26}O_3$ (percent): Molecular weight = 326.42. C, 77.27; H, 8.03. Found (percent): C, 76.9; H, 7.9.

Ultraviolet spectrum (in ethanol):

35

max. at 229 to 230 $m\mu$, $E_{1\text{cm.}}^{1\%} = 190$

max. at 326 to 327 $m\mu$, $E_{1\text{cm.}}^{1\%} = 869$ or $\epsilon = 28,350$

40

This compound is not described in the literature.

EXAMPLE XII

Preparation of 13 β -methyl-17 β -(methylthio) methoxy-2-oxa- $\Delta^{4,9,11}$ -gonatriene-3-one

Under an atmosphere of nitrogen, 1.09 gm. of 13 β -methyl-2-oxa- $\Delta^{4,9,11}$ -gonatriene-17 β -ol-3-one was dissolved in a mixture of 12 cc. of dimethyl sulfoxide and 8 cc. of acetic acid anhydride. The solution was stirred at room temperature for 17 hours and then poured into a mixture of 120 cc. of saturated aqueous solution of sodium bicarbonate and 120 cc. of ice-water. The mixture was stirred for 1 hour and extracted with diethyl ether, the extracts were dried over sodium sulfate and evaporated to dryness under vacuum to yield 1.072 gm. of raw material which was chromatographed through silica gel and eluted with an ethyl acetate-benzene mixture (60-40). Thus were obtained 110 mg. of 13 β -methyl-17 β -(methylthio) methoxy-2-oxa- $\Delta^{4,9,11}$ -gonatriene-3-one having a melting point of about 100° C.

Ultraviolet spectrum (in ethanol):

65 max. at 229 $m\mu$, $E_{1\text{cm.}}^{1\%} = 189$

max. at 326 to 327 $m\mu$, $E_{1\text{cm.}}^{1\%} = 783$ or $\epsilon = 26,200$

A further chromatography through silica gel followed by elution with an ethyl acetate-benzene mixture (2-8), and recrystallization from a methylene chloride-isopropyl ether mixture (1-10) afforded the pure product which had a melting point of 106° C. and a specific rotation $[\alpha]_D^{20} = +98.5^\circ$ (c. = 0.5% in chloroform).

75 This compound is not described in the literature.

EXAMPLE XIII

Preparation of 13β -methyl- 17β -(3'-methyl-2'-butenylloxy)-2-oxa- $\Delta^{4,9,11}$ -gonatriene-3-one

STEP A: PREPARATION OF 5-ETHYLEDIOXY-10-(ETHYLEDIOXY)-METHYL- 13β -METHYL- 17β -(3'-METHYL-2'-BUTENYLOXY)-DES-A- $\Delta^{4,9,11}$ -GONADIENE

3.4 g. of raw 5-ethylenedioxy-10-(ethylenedioxy) methyl- 13β -methyl-DES-A- $\Delta^{4,9,11}$ -gonadiene- 17β -ol (obtained in step B of Example IX) were introduced into 35 cc. of tetrahydrofuran under an atmosphere of nitrogen and then 1 gm. of a suspension of 50% sodium hydride in paraffin oil was added. The mixture was heated to reflux for 30 minutes. Then 6 gm. of 1-bromo-3-methyl-2-butene were introduced therein and the heating at reflux was continued for 2 hours. The reaction mixture was then cooled and subjected to hydrolysis by adding an aqueous solution of sodium bicarbonate. The aqueous layer was extracted with methylene chloride. The combined extracts were washed with water, dried and concentrated to dryness. The residue was taken up with diethyl ether containing 0.5% of triethylamine. The precipitate was vacuum-filtered, and dried, thus affording 3.61 gm. of raw material which was recrystallized from methanol containing 1 part per thousand of triethylamine. Thus, 1.33 gm. of 5-ethylenedioxy-10-(ethylenedioxy) methyl- 13β -methyl- 17β -(3'-methyl-2'-butenylloxy)-DES-A- $\Delta^{4,9,11}$ -gonadiene was obtained, which had a melting point of 144° C. and a specific rotation $[\alpha]_D^{20} = -134^\circ$ (c.=0.5% in chloroform).

Analysis.—Calculated for $C_{24}H_{34}O_5$ (percent): Molecular weight=402.51. C, 71.61; H, 8.51. Found (percent): C, 71.8; H, 8.5.

Ultraviolet spectrum (in ethanol):

max. at 246 m μ , $\epsilon=23,500$

This compound is not described in the literature.

STEP B: PREPARATION OF 10-FORMYL- 13β -METHYL- 17β -(3'-METHYL-2'-BUTENYLOXY)-DES-A- $\Delta^{4,9,11}$ -GONADIENE-5-ONE

Under an atmosphere of nitrogen, 3.4 gm. of raw 5-ethylenedioxy-10-(ethylenedioxy) methyl- 13β -methyl- 17β -(3'-methyl-2'-butenylloxy)-DES-A- $\Delta^{4,9,11}$ -gonadiene were stirred until dissolved, in 26.4 cc. of acetic acid. Next, 8 cc. of water were added and stirring was continued for 1 hour at room temperature. The reaction mixture was poured into 400 cc. of a saturated aqueous solution of sodium bicarbonate, and the aqueous phase was extracted with methylene chloride. The extracts were washed with water, dried and evaporated to dryness, thus yielding 2.9 gm. of 10-formyl- 13β -methyl- 17β -(3'-methyl-2'-butenylloxy)-DES-A- $\Delta^{4,9,11}$ -gonadiene-5-one. This product was used as such for the next step.

Ultraviolet spectrum (in ethanol):

max. at 230 m μ , $E_{1\text{cm.}}^{1\%}=195$

max. at 308 m μ , $E_{1\text{cm.}}^{1\%}=505$ or $\epsilon=15,860$

This compound is not described in the literature.

STEP C: PREPARATION OF 10-HYDOXYMETHYL- 13β -METHYL- 17β -(3'-METHYL-2'-BUTENYLOXY)-DES-A- $\Delta^{4,9,11}$ -GONADIENE-5-ONE

Under an atmosphere of nitrogen, 2.71 gm. of 10-formyl- 13β -methyl- 17β -(3'-methyl-2'-butenylloxy)-DES-A- $\Delta^{4,9,11}$ -gonadiene-5-one were introduced into 30 cc. of tetrahydrofuran; the mixture was cooled to +5° C. and 2.95 gm. of lithium hydridotri isobutoxolaluminate were added thereto. The whole was stirred for 30 minutes at +5° C., then diluted with water and brought to a pH of 3.5 by addition of acetic acid. The aqueous layer was extracted with diethyl ether. The extracts were first washed with an aqueous solution of sodium chloride, then with an aqueous solution of sodium bicarbonate and again with the solution of sodium chloride. The extracts were then dried and evaporated to dryness. The residue was chromatographed over silica gel to afford 1.35 g. of 10-

hydroxymethyl- 13β -methyl- 17β -(3'-methyl-2'-butenylloxy)-DES-A- $\Delta^{4,9,11}$ -gonadiene-5-one.
Ultraviolet spectrum (in ethanol):
max. at 287 to 288 m μ , $\epsilon=19,960$

5 This compound is not described in the literature.

STEP D: PREPARATION OF 13β -METHYL- 17β -(3'-METHYL-2'-BUTENYLOXY)-2-OXA- $\Delta^{4,9,11}$ -GONATRIENE-3-ONE

(1°) Reformatsky reaction: Under an atmosphere of nitrogen, 1.33 gm. of 10-hydroxymethyl- 13β -methyl- 17β -(3'-methyl-2'-butenylloxy)-DES-A- $\Delta^{4,9,11}$ -gonadiene-5-one was dissolved in 20 cc. of tetrahydrofuran. Then 22 cc. of a 0.75 M solution of zinc derivative of ethyl bromoacetate in dimethoxymethane were added to the solution thus obtained. The reaction mixture was agitated for 45 minutes at room temperature. 100 cc. of ice-water were added, the mixture was acidified with 10 cc. of 2 N hydrochloric acid and extracted with methylene chloride. The extracts were washed with water, dried over sodium sulfate and evaporated to dryness, thus yielding 1.8 gm. of material which was used as such for the next step.

(2°) Acid treatment: Under an atmosphere of nitrogen, 1.8 gm. of the material obtained under (1°) was dissolved in 25 cc. of acetone, and 5.6 cc. of 2 N hydrochloric acid were added. The mixture was stirred at room temperature for 2 hours, then diluted with water and extracted with methylene chloride. The extracts were washed with water, dried over sodium sulfate, treated with charcoal, evaporated to dryness, and subjected to chromatography through silica gel to yield 0.383 gm. of 13β -methyl- 17β -(3'-methyl-2'-butenylloxy)-2-oxa- $\Delta^{4,9,11}$ -gonatriene-3-one having a specific rotation $[\alpha]_D^{20} = +52^\circ \pm 2.5$ (c.=0.5% in chloroform).

Ultraviolet spectrum (in ethanol):

max. at 230 m μ , $\epsilon=6,360$

max. at 326 to 327 m μ , $\epsilon=25,550$

This compound is not described in the literature.

EXAMPLE XIV

Pharmacological Study

Determination of the anabolic and androgenic activity

The studies were effected according to the technique used by Hershberger (Proc. Soc. Exp. Biol. Med., 83, 175 [1953]), but with a slight modification. Castrated male rats, 25 days old, received the compound studied at daily administration for 10 days with the exception of the 6th day. The animals were treated starting on the day following the castration, and they were sacrificed on the 11th day, 22 to 26 hours after the last administration. An autopsy was performed on each animal at the time of the sacrifice and the organs of interest were removed and weighed, in particular, the raising muscle of the anus (levator ani) and the kidneys for the study of the anabolic and renotropic actions, and the prostate gland and the seminal vesicles for the study of the androgenic effect.

(A) 13β -METHYL- 17β -ACETOXY-2-OXA- $\Delta^{4,9,11}$ -GONATRIENE-3-ONE

13β -methyl- 17β -acetoxy-2-oxa- $\Delta^{4,9,11}$ -gonatriene-3-one was administered by subcutaneous means, in solution in olive oil containing 5% of benzylic alcohol, at total doses of 100 γ and 1000 γ . The compound was also given orally either in olive oil at a total dose of 1000 γ , or as an aqueous suspension (water containing carboxymethyl cellulose) at a total dose of 5000 γ . (Total doses=the doses divided into 9 administrations over a period of 10 days.)

The following tables summarized the results obtained. In these tables are given, as comparison, the results obtained under the same experimental conditions, with the 17-nor-testosterone acetate administered subcutaneously, in a solution in olive oil containing 5% of benzylic alcohol at total doses of 200 γ and 1000 γ , and with the 17 α -methyl-19-nor-testosterone administered orally, as an aqueous suspension (water containing carboxymethyl cellulose) at total doses of 10 and 50 mg.

TABLE I.—SUBCUTANEOUS ADMINISTRATION

TABLE II.—ORAL ADMINISTRATION

Lots	Weight of animals		Fresh kidneys in grams per 1,000 grams of rat	Dry kidneys, mg.	Dry kidneys in grams per 1,000 grams of rat	Fresh levator ani in grams per 1,000 grams of rat	Dry levator ani in grams per 1,000 grams of rat	Seminal vesicles, mg.	Prostate, mg.

Controls 17 α -methyl-1 β -acetoxy-2 α -oxo- Δ^4 ,11,16a-triene-3-one	1,000 γ $\times$ 10	0	48	83	441.3	5.310	97.1	1.167	12.8
		9			522.6	5.838	110.4	1.233	32.7
17 α -methyl-19-nor-testosterone	5,000 γ $\times$ 10	48	79	483.5	6.340	102.1	1.321	48.1	0.631
		9						10.2	0.134

These results demonstrate that 13β -methyl- 17β -acetoxy-2-oxa- $\Delta^{4,9,11}$ -gonatriene-3-one presents anabolic and androgenic activities superior to those of 19-nor-testosterone acetate, when subcutaneously administered, and even more distinctly superior to those of the 17α -methyl-19-nor-testosterone when orally administered.

(B) 13β -METHYL- 17β -(METHOXY)-METHOXY-2-OXA- $\Delta^{4,9,11}$ -GONATRIENE-3-ONE

13β -methyl- 17β -(methoxy)-methoxy-2-oxa- $\Delta^{4,9,11}$ -gonatriene-3-one, utilized in solution in olive oil, was administered orally at daily doses of

$$4\gamma \times \frac{10}{9}, 20\gamma \times \frac{10}{9}, \text{ and } 100\gamma \times \frac{10}{9}$$

(total doses of 40γ , 200γ and 1000γ , divided into 9 administrations over a period of 10 days).

The results obtained are summarized in the following table, wherein, by virtue of the comparison, the results obtained with 17-methyl-testosterone given at daily doses of 600γ , 3 mg. and 15 mg. are presented (in this case the animals were treated daily over a period of 10 days).

TABLE IV

Lot	Daily dose	Fresh levator ani, mg.	Seminal vesicles, mg.	Prostate gland, mg.
5	Controls-----	0	20.9	4.5
	$10\gamma \times \frac{10}{9}$	42.6	33.0	15.6
	$100\gamma \times \frac{10}{9}$	68.4	202.7	148.6
15	13β -methyl- 17β -benzoyloxy-2-oxa- $\Delta^{4,9,11}$ -gonatriene-3-one-----	$10\gamma \times \frac{10}{9}$	53.3	256.2
	Controls-----	0	19.3	16.3
	$1 mg. \times \frac{10}{9}$	44.4	72.7	87.4
20	Controls-----	0	23.4	7.6
	$19\text{-nor-testosterone acetate}$ -----	$20\gamma \times \frac{10}{9}$	35.7	9.2
		$100\gamma \times \frac{10}{9}$	51.3	34.3

TABLE III.—ORAL ADMINISTRATION

Lots	Daily dose	Weight of animals in grams		Fresh levator ani in grams per 1,000 grams of rat	Seminal vesicles, mg.	Prostate, mg.
		Initial	Final			
Control-----	0	51	95	20.7	0.218	5.0
13β -methyl- 17β -(methoxy)-methoxy-2-oxa- $\Delta^{4,9,11}$ -gonatriene-3-one-----	$4\gamma \times \frac{10}{9}$	52	90	26.5	0.294	7.5
	$20\gamma \times \frac{10}{9}$	56	89	36.7	0.412	9.9
	$100\gamma \times \frac{10}{9}$	55	89	53.7	0.603	65.8
17α -methyl-testosterone-----	600γ	51	77	21.80	0.283	9.2
	3 mg.	49	63	23.60	0.373	32.6
	15 mg.	46	70	37.03	0.529	117.0
						53.8
						166.1

These results demonstrate that 13β -methyl- 17β -(methoxy)-methoxy-2-oxa- $\Delta^{4,9,11}$ -gonatriene-3-one possesses an anabolic activity considerably superior to that of the 17α -methyltestosterone, since at daily doses of 20γ , 13β -methyl- 17β -(methoxy)-methoxy-2-oxa- $\Delta^{4,9,11}$ -gonatriene-3-one exerts an action at least equal to that of the 17α -methyl-testosterone at the daily dose of 3 mg. At the same dose, the androgenic effects of the studied product are very slight.

(C) 13β -METHYL- 17β -BENZOYLOXY-2-OXA- $\Delta^{4,9,11}$ -GONATRIENE-3-ONE

(1) Subcutaneous administration: 13β -methyl- 17β -benzoyloxy-2-oxa- $\Delta^{4,9,11}$ -gonatriene-3-one, utilized in a solution in olive oil containing 5% benzyl alcohol, was subcutaneously administered at daily doses of

$$10\gamma \times \frac{10}{9}, 100\gamma \times \frac{10}{9} \text{ and } 1 mg. \times \frac{10}{9}$$

(total doses of 100γ , 1 mg. and 10 mg., divided into 9 administrations in the first test) and at the daily dose of

$$20\gamma \times \frac{10}{9}$$

(total dose of 200γ) in the second test. The results were compiled in Table IV, wherein, for the purpose of comparison, the results are given which were obtained with $19\text{-nor-testosterone acetate}$ administered in daily doses of

$$20\gamma \times \frac{10}{9} \text{ and } 100\gamma \times \frac{10}{9}$$

under the same test conditions.

(2) Oral administration: The studied product was administered at daily doses of

$$100\gamma \times \frac{10}{9}, 1 mg. \times \frac{10}{9} \text{ and } 10 mg. \times \frac{10}{9}$$

in the first test.

In a second test it was administered at daily doses of

$$20\gamma \times \frac{10}{9} \text{ and } 200\gamma \times \frac{10}{9}$$

The product was utilized in an oily solution; however, it was not entirely dissolved in the larger doses.

The results obtained were compiled in Table V which, for purposes of comparison, presents those obtained with 17α -methyl-19-nor-testosterone administered in daily doses of

$$1 mg. \times \frac{10}{9} \text{ and } 5 mg. \times \frac{10}{9}$$

under identical test conditions.

TABLE V

Lot	Daily dose	Fresh levator ani, mg.	Seminal vesicles, mg.	Prostate gland, mg.
Controls.....	0	13.8	7.0	9.0
13 β -methyl-17 β -benzoyloxy-2-oxa- Δ 4,9,11-gonatriene-3-one.....	100 γ $\times$ $\frac{10}{9}$	38.2	22.3	37.6
	1 mg. $\times$ $\frac{10}{9}$	51.6	122.5	119.0
	10 mg. $\times$ $\frac{10}{9}$	55.1	181.2	140.8
Controls.....	0	19.3	16.3	14.1
13 β -methyl-17 β -benzoyloxy-2-oxa- Δ 4,9,11-gonatriene-3-one.....	20 γ $\times$ $\frac{10}{9}$	29.6	10.8	15.0
	200 γ $\times$ $\frac{10}{9}$	41.3	38.2	47.7
Controls.....	0	12.8	5.7	10.3
17 β -methyl-19-nor-testosterone.....	1 mg. $\times$ $\frac{10}{9}$	32.7	18.2	28.1
	5 mg. $\times$ $\frac{10}{9}$	48.1	36.8	74.7

These results demonstrate that 13 β -methyl-17 β -benzoyloxy-2-oxa- Δ 4,9,11-gonatriene-3-one possesses an anabolisant and androgenic activity distinctly superior to that of the comparison products, administered subcutaneously as well as orally.

(D) 13 β -ETHYL-17 β -ACETOXY-2-OXA- Δ 4,9,11-GONATRIENE-3-ONE

13 β -ethyl-17 β -acetoxy-2-oxa- Δ 4,9,11-gonatriene - 3 - one utilized as a solution in olive oil admixed with 5% of benzyl alcohol, was administered subcutaneously at daily doses of

10 γ $\times$ $\frac{10}{9}$ and 100 γ $\times$ $\frac{10}{9}$

(total doses of 100 γ and 1 mg. divided into nine administrations over a period of ten days).

The results obtained are compiled in Table VI wherein, for the purpose of comparison, the results obtained with the 19-nor-testosterone acetate, under the same test conditions, administered at total doses of 200 γ and 100 γ , are presented.

TABLE VI

Lots	Daily dose	Fresh levator ani, mg.	Seminal vesicles, mg.	Prostate gland, mg.
Controls.....	0	20.9	4.5	8.2
13 β -ethyl-17 β -acetoxy-2-oxa- Δ 4,9,11-gonatriene-3-one.....	10 γ $\times$ $\frac{10}{9}$	51.0	95.9	102.2
	100 γ $\times$ $\frac{10}{9}$	53.0	170.8	164.8
Controls.....	0	21.4	7.6	10.3
	20 γ $\times$ $\frac{10}{9}$	35.7	9.2	15.5
19-nor-testosterone acetate.....	0	51.3	27.1	34.3
	100 γ $\times$ $\frac{10}{9}$			

The results demonstrate that 13 β -ethyl-17 β -acetoxy-2-oxa- Δ 4,9,11-gonatriene-3-one exhibits at the daily dose of 10 γ , an anabolisant activity far superior to that of 19-nor-testosterone acetate at the dose of 20 γ , and that at the dose of 100 γ , the two products show an appreciably uniform activity. Besides, the studied product is considerably more androgenic than the comparison product.

The studied product administered orally under the same test conditions and utilized as a solution in olive oil, proved to be active at the daily dose of

100 γ $\times$ $\frac{10}{9}$

As it has been previously mentioned, the compounds of the general Formula I are endowed with interesting pharmacological properties. In particular, they possess an important anabolic action as well as an androgenic action.

They can be utilized for the treatment of disorders of proteinic anabolism, asthenia, underweight, osteoporosis, andropause, senescence, slow consolidation of fractures, metabolic disorders of prolonged corticotherapy, adiposogenital syndrome, functional menometrorrhagia, fibromes, endometriosis, and also as supplemental treatment of breast cancer.

For external application they can be employed as cicatrization agent for wounds or varicose ulcers.

The novel 13 β -R-17 β -OX - 2 - oxa - Δ 4,9,11 - gonatriene-3-ones of the general Formula I are used orally, perlingually, parenterally, transcutaneously, rectally or subcutaneously.

They can be prepared in the form of injectable or drinkable solutions or suspensions, put up in ampules, in multiple-dose flacons, in implants, in tablets, in capsules, in coated tablets, in sublingual tablets, in suppositories, in solutions for transcutaneous usage and in creams or pomades.

The useful dosology is controlled between 0.003 mg./25 kg. and 0.3 mg./kg. per day in warm-blooded animals or 0.200 mg. and 20 mg. per day for the adult as a function of the method of administration and of the therapeutic indication.

The preceding specific embodiments are illustrative of 30 the invention. It is to be understood, however, that other expedients known to those skilled in the art may be employed without departing from the spirit of the invention or the scope of the appended claims.

We claim:

35 1. An unsaturated 2-oxa steroid derivative selected from the group consisting of (a) compounds of the formula

wherein X' is selected from the group consisting of alkoxy having 1 to 4 carbon atoms, cyclohexyl, alkylthio having 1 to 4 carbon atoms, alkenyl having from 2 to 4 carbon atoms and phenyl and (b) compounds of the formula

60 wherein R is alkyl having from 2 to 6 carbon atoms, X is selected from the group consisting of hydrogen, alkyl having from 1 to 5 carbon atoms, alkenyl having from 3 to 5 carbon atoms, cycloalkyl having from 5 to 7 carbon atoms, phenylalkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms.

65 2. The unsaturated 2-oxa steroid derivative of claim 1, compound (a), wherein X' is methoxy.

3. The unsaturated 2-oxa steroid derivative of claim 1, compound (a), wherein X' is cyclohexyl.

4. The unsaturated 2-oxa steroid derivative of claim 1, compound (b), wherein R is ethyl and X is hydrogen.

31

5. The unsaturated 2-oxa steroid derivative of claim 1, compound (b), wherein R is ethyl and X is acetyl.

6. The unsaturated 2-oxa steroid derivative of claim 1, compound (b), wherein R is ethyl and X is benzoyl.

7. The unsaturated 2-oxa steroid derivative of claim 1, compound (a), wherein X' is 1-methyl-vinyl.

8. The unsaturated 2-oxa steroid derivative of claim 1, compound (a), wherein X' is 2-methyl-1-propenyl.

9. A process for the production of an unsaturated 2-oxa steroid derivative of the formula

wherein R is alkyl having from 1 to 6 carbon atoms, X is selected from the group consisting of hydrogen, alkyl having from 1 to 5 carbon atoms, alkenyl having from 3 to 5 carbon atoms, cycloalkyl having from 5 to 7 carbon atoms, phenylalkyl having from 7 to 11 carbon atoms, cycloalkylalkyl having from 6 to 11 carbon atoms, alkylthioalkyl having from 2 to 5 carbon atoms, alkoxyalkyl having from 2 to 5 carbon atoms, and the acyl of an organic carboxylic acid having from 1 to 18 carbon atoms, which comprises the steps of condensing a 10-hydroxymethyl-des-A- $\Delta^{9,11}$ -gonadiene-5-one of the formula

wherein R and X have the above-assigned meanings, with a lower alkyl haloacetate in the presence of zinc, reacting the resulting condensation products, a mixture (1) a 5 - alkoxy carbonylmethyl - 10 - hydroxymethyl - des-A- $\Delta^{9,11}$ -gonadiene of the formula

wherein R and X have the above-assigned meanings and alkyl represents a lower alkyl, and (2) a 2 - oxa - $\Delta^{9,11}$ -gonadiene-ol-3-one of the formula

wherein R and X have the above-assigned meanings, with a strong acid, and recovering said unsaturated 2-oxa steroid derivative.

10. The process of claim 9 wherein said strong acid is selected from the group consisting of hydrochloric acid, sulfuric acid, perchloric acid, p-toluenesulfonic acid and methane sulfonic acid.

32

11. A process for the production of an unsaturated 2-oxa steroid derivative of the formula

wherein R is alkyl having from 1 to 6 carbon atoms, which comprises the steps of

(a) condensing a 10 - hydroxymethyl - des - A - $\Delta^{9,11}$ -gonadiene 5-one of the formula

wherein R is alkyl having from 1 to 6 carbon atoms and acyl represents the acyl residue of an organic carboxylic acid having from 1 to 18 carbon atoms, with a lower alkyl haloacetate in the presence of zinc,

(b) saponifying the resulting condensation mixture consisting of

(1) a 5 hydroxy 5-alkoxycarbonylmethyl 10-hydroxy methyl-des-A- $\Delta^{9,11}$ -gonadiene of the formula

(2) 5 β - 17 β - hydroxy 2-oxa- $\Delta^{9,11}$ -gonadiene-3-one of the formula

wherein R has the above stated meaning, to the action of a strong acid dehydrating agent and

(c) recovering said 2-oxa 3-oxa 17 β -hydroxy gonatriene of the formula

12. The process of claim 11 wherein said unsaturated 2-oxa steroid derivative is subjected to the action of an esterification derivative of an organic carboxylic acid having from 1 to 18 carbon atoms selected from the group

33

consisting of the acid, the acid anhydride and the acid chloride.

13. The process of claim 11 wherein said unsaturated 2-oxa steroid derivative is subjected to the action of an etherification agent selected from the group consisting of dialkyl sulfoxide having from 2 to 5 carbon atoms in the presence of an organic carboxylic acid anhydride and alkoxyalkyl halide having from 2 to 5 carbon atoms.

14. The process of claim 11 wherein said strong acid is selected from the group consisting of hydrochloric acid, sulfuric acid, perchloric acid, p-toluene sulfonic acid and methane sulfonic acid.

34

15. The process of claim 11 wherein said saponifying agent is an alkali metal hydroxide in the presence of a lower alkanol.
